8 Claims. (Cl. 74—151)

The invention concerns a driving mechanism for imparting stepped advance movements to a rotatable cylinder shaft from a continuously rotating drive shaft, the preferred use of the mechanism being in dobbies with a cylinder for paper cards, or lag and pegs, or iron rollers.

The control of dobbies is provided by means of strip-like control cards provided with pins or with punched holes so as to be able to read off data when using the latter, in the control process the cards must stop exactly at the predetermined spot, as this makes it possible for the reading needle to fall unhindered into the holes.

The stepped advance of the cylinder shaft takes place in the known way by crank shaft and eccentric, by means of a worm gearing or by a pin disposed on a rotating disc, which on each rotation engages a tooth of a toothed wheel on the cylinder shaft and carries this along to the extent of at least one tooth. With these known devices, the stepped turning of the cylinder is jerky. With each engagement of the forwarding mechanism there is brusque movement which leads to great wear and tear and to undesirable vibrations.

With the new driving mechanism, there is a smoother passing over from standstill to the advance movement in that the operational diagram shows a sinusoidal curve. This mechanism has the feature that the drive shaft has a cam profile means and the cylinder shaft a toothed wheel and that there are disposed two bellcrank levers the first lever being pivotable at a fixed pivot, and that one free end of this first lever is connected to the cam means, whereas the other free end of this first lever is pivotally connected to the apex of the second lever, and that, furthermore, one free end of this second lever is connected to the same cam means and the other free end of this second lever engages the toothed wheel.

The invention will now be described with reference to the embodiments of the subject-matter of the invention shown in the drawings.

FIG. 1 is a top view of the drive mechanism of the cylinder shaft.

FIG. 2 is a side view of the drive mechanism, in which the drive shaft and the cylinder shaft have the same direction of rotation.

FIG. 3 is the diagram showing the above.

FIGS. 4a, 4b, 4c and 4d are diagrammatic representations of the work positions of the driving mechanism.

FIGS. 5a, 5b, 5c and 5d are diagrammatic representations of the driving mechanism with counterrunning direction of rotation of drive shaft and cylinder shaft.

On the drive shaft 1 there is a cam profile 2, which in FIGS. 1 and 2 is shown with grooved profile and in FIGS. 4 and 5 with cog profile. The toothed wheel 3 is fixed on the cylinder shaft 4. In FIGS. 4 and 5 the toothed wheels are shown as discs.

The bellcrank lever 5, having arms 5a and 5b, is pivotally disposed in the fixed shaft 6, whereas the bellcrank lever 7, with arms 7a and 7b, is pivotally fixed on arm 5b at 8. The arms 5a and 5b of the lever 5 form an obtuse angle, and those of the double lever 7 an acute angle.

The arms 5a and 7a each have a roller 9 or 10 which either follow the contour of an open cam or engage in the groove of the cam 2. To enable the other end

2

of the second lever to engage in the toothed wheel 3, a bolt 11, is provided, fixed on the arm 7b.

Essentially, the contour of the cam profile 2 consists of arcuate profile portions A and C and the contour profile portions B and D.

The separate operations will now be described in reference to FIGS. 4a, 4b, 4c and 4d. For disengaging the bolt 11 from the toothed wheel 3, the lever 5 in this representation is tilted counter-clockwise from the contour portion D. The center of rotation 8 for the lever 7 is raised and the bolt 11 slides out, as shown in FIG. 4a. Movement of the contour portion D then takes place, and this portion glides under the roller 10 and tilts the lever 7, the lever 5 and with it also the center of rotation 8 of the lever 7 remaining unchanged. The return of the control bolt 11 accordingly takes place.

FIG. 4b shows the position after the return is completed. For the engagement of the bolt in the toothed wheel, the lever 7 remains in unchanged position, since the roller glides over the arcuate profile portion A. On the other hand, the contour portion B raises the roller 9, which gives pivotal movement to the lever 5 about the fixed pivot 6, whereupon the lever 7 drops and the bolt engages in the toothed wheel, as shown in FIG. 4c. The actual driving operation is effected by the contour profile B raising the roller 10 so that the arm 7a, and with it also the arm 7b, pivots at pivot point 8.

In contrast to the embodiment described, the two shafts 1 and 4 in the embodiment of the FIGS. 5a, 5b, 5c and 5d rotate counter-clockwise. The first lever 5 is here nearer to the two shafts 1 and 4 than the second lever, or the apex of the bellcrank lever is located outside the triangle defined by the driving axis 1, the cylinder axis 4 and the fixed pivot 6, whereas with the first described example, the second lever is located between the two shafts 1 and 4, i.e. between the fixed pivot 6 and the shaft 4.

FIG. 5a shows the mechanism after the driving operation and before the bolt 11 has been disengaged from the toothed wheel 3, which takes place by the cooperation of the contour portion D with the roller 9. The return of the bolt 11 in relation to the toothed wheel takes place by the cooperation of the contour portion D with the roller 10, that is to say, the lever 7 is tilted, whereas the lever 5 is motionless, as can be seen by comparing FIG. 5b with FIG. 5c. To engage, the roller 9 drops over the contour portion B, whereas the roller 10 rolls over the arcuate portion C, the lever 7 remaining motionless. When the lever 10 rolls over the contour part B, as can be seen by comparing FIG. 5d with FIG. 5a the lever 7 pivots, and the actual driving operation at the toothed wheel 3 takes place with the pivot point 8 motionless, since the roller 9 glides over the arcuate portion A.

From the details of functioning given, it can be seen that whilst a contour portion B, D cooperates with an arm or its roller, the other arm or its roller always engages with an arcuate profile portion A, C, so that duplicated movements of the levers are excluded, that is to say each lever carries out a movement which is exactly planned for it alone.

The device permits a smooth, that is to say not jerky transfer from one position to the other. FIG. 3 shows the sinusoidal-like forward movement of the toothed wheel and, accordingly, of the cylinder shaft with its controlled card.

I claim:

1. A driving mechanism for imparting stepped advance movements to a rotatable cylinder shaft from a continuously rotating drive shaft, which includes cam profile means secured to said drive shaft, a toothed wheel se-

cured to said cylinder shaft, a first bellcrank lever, a fixed pivot for said first lever, means connecting one free end of said first lever to said cam means whereby said free end follows the profile of the cam means, a second bellcrank lever, means pivotally connecting the other free end of said first lever to the apex of the second lever, means connecting one free end of said second lever to said cam means whereby said free end follows the profile of the cam means, and means at the other free end of said second lever for engaging said toothed wheel.

2. A driving mechanism according to claim 1, wherein said means connecting one free end of said first and second levers to said cam means comprise rollers mounted at said free ends.

3. A driving mechanism according to claim 1, wherein said means for engaging said toothed wheel consists of a bolt provided at said other free end of said second lever.

4. A driving mechanism according to claim 1, wherein the profile of the said cam means includes first and second arcuate profile portions and first and second contour profile portions, which profile portions are disposed so that each contour portion is followed by the said one free end of each lever when the other contour portion is not being followed by the said one free end of the other lever, whereby the said lever free end of said second lever is caused to perform four separate movements of starting, lifting, return and engagement.

5. A driving mechanism according to claim 1, wherein the angle between the two arms of the first lever is greater than the angle between the two arms of the second lever.

6. A driving mechanism according to claim 1, wherein the apex of the second lever lies outside the triangle defined by the axis of the cylinder shaft, the axis of the drive shaft, and the said fixed pivot.

7. A driving mechanism according to claim 1, wherein

the second lever is located between the said fixed pivot and the axis of the cylinder shaft.

8. A driving mechanism which includes a drive shaft continuously rotating, a cylinder shaft, parallel to the said drive shaft, with a toothed wheel mounted on it, cam profile means secured to said drive shaft, first and second arcuate profile portions defined as said cam profile, and concentric with said drive shaft, first and second contour profile portions defined on said cam profile, a first lever, means pivotably mounting said first lever about a fixed fulcrum between its ends, means for causing one end of said first lever to follow the profile of said cam means, a second lever, means pivotably connecting the other end of the first lever to a point on the second lever between its ends, means for causing one end of said second lever to follow the profile of said cam means at a point spaced from the end of the first lever so that when one end of either lever is following a contour profile portion the one end of the other lever is following an arcuate profile portion, and means at the other free end of said second lever for engaging said toothed wheel, the arrangement being such that the said other free end of said second lever is caused to perform four separate movements of starting, lifting, return and engagement.
